UNITED STATES PATENT OFFICE.

WILLIAM A. SUSSMILCH, OF ROCKFORD, ILLINOIS.

PALETTE.

SPECIFICATION forming part of Letters Patent No. 716,140, dated December 16, 1902.

Application filed June 5, 1902. Serial No. 110,261. (No model.)

To all whom it may concern:

Be it known that I, WILLIAM A. SUSSMILCH, a citizen of the United States, residing at Rockford, in the county of Winnebago and State of Illinois, have invented certain new and useful Improvements in Palettes, of which the following is a specification.

The object of this invention is to provide a palette with markings to indicate the location of the pigments and also with means for holding pigment-containing receptacles in position to discharge the pigment at the proper places on the palette.

In the accompanying drawings, Figure 1 is a face representation of the palette. Fig. 2 is a section on dotted line *a*, Fig. 1.

The palette 1 is of the usual outline. The face of the palette at the end opposite the thumb-opening 2 has a circular outline bounded by the six curved sides 3, 4, 5, 6, 7, and 8. Adjacent to the curved sides 3, 5, and 7 are located pigment-containing tubes 9, 10, and 11, each held in place by elastic bands 12, passing through openings in the palette and secured to the under face of the palette.

A pigment-containing tube 13 is held in place by the elastic bands 14 in the same manner that the other tubes are held.

By means of the six-sided figure the location of the three prime colors and the three principal hues are indicated.

In securing the pigment-containing tubes to the palette and arranging them so that the pigment will be discharged at the proper place, the tube is always at the place desired and errors and annoyances resulting from carelessly-arranged pigments cannot happen.

In arranging for a painting pigments are chosen representative of the three prime colors, and the tubes containing them are placed under the elastic bands.

The tube 13 is designed to hold white pigment and is located in the upper right-hand corner of the palette.

I claim as my invention—

1. A palette having pigment-containing tubes located on its face and bands encircling the tubes and holding them in position.
2. A palette having pigment-containing tubes located on its face and elastic bands encircling the tubes and holding them in position.
3. A palette having pigment-containing tubes located on its face, openings through the palette and bands encircling the tubes and passing through the openings.
